(57) **CLAIM**

The ornamental design for a handle for a back brush, as shown and described.

DESCRIPTION

FIG. 1 is a perspective view of a handle for back brush showing the claimed design;

FIG. 2 is another perspective view of a handle for back brush showing the claimed design;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of an area labeled 9 in FIG. 1;

FIG. 10 is another partial enlarged view of an area labeled 10 in FIG. 2; and,

FIG. 11 is a exploded view thereof.

The dot-dash broken lines in FIGS. 1, 2, 9 and 10 are included to show partially enlarged views only, while all other broken lines are included for the purpose of illustrating portions of the handle for back brush; the broken lines form no part of the claimed design.
